UNITED STATES PATENT OFFICE.

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

TURBINE-ENGINE.

1,184,830.

Specification of Letters Patent. Patented May 30, 1916,

Application filed August 4, 1913. Serial No. 782,975.

To all whom it may concern:

Be it known that I, CHARLES W. DAKE, a citizen of the United States, residing at Chicago, in the county of Cook and State of Illinois, have invented a certain new and useful Improvement in Turbine-Engines, of which the following is a specification.

My invention relates to improvements in turbines.

It is illustrated diagrammatically in one form in the accompanying drawings, wherein—

Figure 1 is an end elevation in part section with some parts removed; Fig. 2 is a section along line 2—2 of Fig. 1; Fig. 3 is an elevation of one of the buckets; and Fig. 4 is a section along the line 4—4 of Fig. 3.

Like parts are indicated by like letters throughout the several figures.

A is a turbine housing having a cover A¹ and having projecting from the opposed side thereof a sleeve A² which sleeve is provided for the purpose of connecting the turbine housing with the housing of some driven machine such as an electric generator not shown.

A³ is a bearing supported in the sleeve A², and A⁴ is a shaft rotatably mounted in the bearing.

A⁵ is a spider mounted on a hub A⁶ which hub is in turn mounted on the shaft A⁴. It will be noted that the rear wall of the housing A is apertured as at A⁷ to permit the shaft A⁴ to pass through, and that packing rings A¹¹ and A¹² are provided to close this aperture and make the housing tight.

B, B are turbine buckets grouped about the periphery of the spider A⁵ and provided with lugs B¹ engaging the recess B² in the spider and locked in position by the ring B³. These buckets are arranged side by side as indicated in Fig. 1 so as to make a continuous series of buckets about the periphery of the wheel. They are provided with the inwardly extending extensions B⁴ which project inwardly away from or beyond the lip of the bucket toward the center of the rotor when assembled, thus forming an annular free space or channel around the spider between the lips of the buckets and the steam supply nozzle. An annular ring B⁵ rests upon the sides of the buckets farthest removed from the spider and is held in position by the screws B⁶, its function be-

ing to reinforce the outer sides of the buckets and hold them rigidly together, thus adding to the strength and durability of the rotor and obviating the danger of displacement or distortion of the buckets.

C is the discharge or expanding steam nozzle discharging into the annular free space and through it into the buckets.

C¹ is an annular steam chamber connected by the passage C² to the nozzle C.

C³ is a valve plug located within the annular chamber C¹ containing the valve C⁴, the valve seat C⁵ and an annular steam chamber C⁶ in communication by means of the passage ways C⁷ with the annular chamber C¹ and also connected with the passage C⁸ controlled by the valve C⁴.

C⁹ is a steam chamber communicating with the passage C⁸ and connected with any suitable source of steam supply not shown by the pipe C¹⁰.

D is a governor shown in elevation driven from the shaft A⁴ and adapted to operate the bell crank lever D¹ pivoted on the bracket D² to manipulate or operate the valve C⁴ against the spring D³ to control the supply of steam.

E is an exhaust chamber located outside of the buckets on the spider and communicating with the interior of the casing through the elongated passage way or port E² which port is closed by the buckets B as they pass along. This chamber discharges through the exhaust pipe E³ at any suitable exhaust point. A guide wall E⁴ is provided in front of the nozzle C coming down to a point adjacent the inner edge of the free annular space formed by the bucket extensions B⁴ to form what is in effect a nozzle-shaped passage or port from the interior of the housing to the exhaust chamber, this port or passage being interrupted by or containing within itself the rapidly moving bucket carrying rim of the rotor.

The use and operation of my invention are as follows: With the parts in the position shown, the valve being held open by the spring, the engine will be started by admitting steam through the steam passage and nozzle to the bucket wheel. This steam will be controlled, of course, by a throttle of the ordinary type which I have not illustrated. The steam as it passes through the steam nozzle will increase in velocity from 1450

2

feet per second to 3000 feet per second, and this rapidly moving column of steam will impinge upon the buckets or vanes and exert a force upon them which will rotate the bucket wheel. The column of steam will after impinging upon the buckets pass through them and be discharged from the opposite side of the nozzle from which it entered. It will rapidly pass out through 5 the exhaust chamber and the exhaust pipe. The nozzle, it will be noted, does not come into immediate close contact with the buckets but discharges into the free annular space or ring inside the bucket lips. Under 10 ordinary circumstances the steam may pass rapidly through this space without waste or overflow and be discharged into the buckets. If, however, the turbine should be carrying an overload or if for any other 15 cause any individual bucket becomes choked with steam, then the steam instead of backing up into the nozzle and causing a reduction of velocity and other disastrous difficulties will immediately overflow through 20 this free annular space, which for this purpose acts as a by-pass, into the adjacent bucket which bucket will meanwhile having left the nozzle have time to become clear of steam. Thus, instead of having one bucket 25 at work, you might have a number of buckets at work, all of them carrying a portion of the load. There is thus no tendency for the steam to leak over the sides of the buckets or be dissipated by the atmosphere within 30 the casing, since this is guarded against by the annular ring bounding the free space, and no tendency for the steam to back up into the nozzle because it can more easily overflow through an adjacent bucket. 35

40 The steam, as above noted, leaves the turbine at a relatively high rate of speed and passes rapidly through a port registering with the buckets and out through the exhaust chamber and exhaust pipe. This, of course, has a tendency to cause a vacuum in 45 the interior of the housing or casing in the usual manner, and thus all leakage will be drawn out of the interior of the housing, passing through those buckets not in line 50 with the nozzle into the exhaust chamber, and a vacuum of greater or less intensity as the case may be will then exist in the interior of the turbine housing, and this vacuum, of course, will cause a reduction of air 55 friction on the turbine rotor and add to the power of the engine. Moreover, the products of leakage, oil, air, water or the like such as may be drawn up through the buckets of the turbine, passing as they do through 60 the nozzle-shaped passage leading from the interior of the housing to the exhaust port, will to a certain extent at least assist by impinging upon the turbine buckets in driving or rotating the bucket wheel. The operation 65 of the governor shown in elevation needs no

explanation here. Suffice it to say that it operates in the usual manner and will hold the speed of rotation constant or fixed and independent of changes in the load. The interior of the housing thus forms what I prefer to call a governor chamber. It is a chamber which in this particular instance contains the governor or part of it together with other parts such as the valve and the like. This chamber is in form substantially equivalent to the total interior of the housing and it is this chamber which is kept free of escaping steam and air and wherein the actual pressure is kept below atmospheric by the peculiar arrangement of the parts as set forth. By governor chamber I, therefore, mean that chamber which contains the moving parts and which in the present instance is partially bounded at one point by the bucket wheel itself. 85

I claim:

1. A fluid turbine having a supply nozzle, a bucket wheel, and a channel for guiding the overflow from one bucket into and through the preceding bucket, said channel of a cross section substantially equal to or greater than the difference between the cross section of the nozzle and the effective bucket opening. 90

2. A fluid turbine having a supply nozzle, a bucket wheel, and an annular channel on said bucket wheel in front of the buckets and between them and the nozzle, said channel of a cross section substantially equal to or greater than the difference between the cross section of the nozzle and the effective bucket opening. 95

3. A fluid turbine having a supply nozzle, a bucket wheel, and an annular channel interposed between the buckets and the nozzle, said channel of a cross section substantially equal to or greater than the difference between the cross section of the nozzle and the effective bucket opening. 100

4. A fluid turbine having a supply nozzle, a bucket wheel, and means for guiding the overflow from one bucket into and through the preceding bucket, said means comprising an annular channel interposed between the buckets and the nozzle, said channel of a cross section substantially equal to or greater than the difference between the cross section of the nozzle and the effective bucket opening. 110

5. A fluid turbine having a bucket wheel, a supply nozzle discharging into said wheel against the buckets, said nozzle being removed from the lips of the buckets, and a channel interposed between said nozzle and said buckets for preventing the waste of steam past the buckets, said channel of a cross section substantially equal to or greater than the difference between the cross section of the nozzle and the effective bucket opening. 120

6. A fluid turbine having a bucket wheel, a supply nozzle discharging into said wheel against the buckets, said nozzle being removed from the lips of the buckets, and means interposed between said nozzle and said buckets for preventing the waste of steam past the buckets, said means comprising an annular channel interposed between the buckets and the nozzle, said channel of 10 a cross section substantially equal to or greater than the difference between the cross section of the nozzle and the effective bucket opening.
7. A turbine comprising a housing for 15 the rotating parts, a governor chamber contained therein, a bucket wheel rotating therein, a supply nozzle located therein and discharging against said bucket wheel outwardly, and an exhaust chamber in communication with said housing, the communication between said exhaust chamber and said governor chamber being closed by the bucket wheel.
8. A turbine comprising a housing for the 20 rotating parts, a governor chamber contained therein, an exhaust chamber, an annular port interposed between them, and a bucket wheel rotating within the housing, the buckets of said bucket wheel passing through and closing said annular port.
9. A turbine comprising a housing for the 25 rotating parts, a governor chamber contained therein, an exhaust chamber, an annular port interposed between them, a bucket wheel rotating within the housing, the buckets of said bucket wheel passing through and closing said annular port, and a supply nozzle located within said governor chamber and discharging against said 30 buckets and through said port.
10. A turbine comprising a housing for 35 rotating parts and an exhaust chamber, a connection between them, a bucket wheel rotating within said housing and passing through the connection between the housing and the chamber, a supply nozzle, and means for inducing a current from the interior of said housing through said wheel to the exhaust chamber.
11. A turbine comprising a housing for 40 the rotating parts, a governor chamber contained therein, a rotor inclosed throughout the major part of its length, and a single exhaust port and exhaust chamber, said port interposed between said exhaust chamber and said governor chamber, said buckets passing through said port.
12. A turbine comprising a housing for 45 rotating parts, a bucket wheel rotating therein and an exhaust chamber in communication with said housing, the communication between said exhaust chamber and said housing being closed by the bucket wheel.
13. A turbine comprising a housing for 50 rotating parts, a bucket wheel, means for introducing steam at high velocity and impinging it against the bucket wheel and for discharging it from the turbine at relatively high velocity, a nozzle-shaped aperture interposed between said buckets and the housing, and an exhaust port in line with said nozzle-shaped aperture.
14. A fluid turbine having a rotor, an exhaust chamber on one side thereof and a nozzle and housing for rotating parts on the other side, openings on opposite sides of the rotor, the opening on the exhaust side being larger than the nozzle.
15. A fluid turbine having a housing for 55 rotating parts, a nozzle therein, an exhaust chamber, a rotor wheel, a channel for the same between the housing and exhaust chamber, the buckets of the rotor wheel placed so as to form an annular opening between the edges of the buckets and the edge of the rotor wheel, a nozzle in the housing chamber and an opening from the housing chamber, both directed so as to deliver diagonally across the rotor wheel.
16. A fluid turbine having a central housing chamber containing moving parts, a rotor having an annular peripheral propeller ring located therein adjacent the periphery thereof, an exhaust chamber outside of the 60 rotor separated by it from and communicating only through it with the central chamber.
17. A fluid turbine having a central housing chamber containing moving parts, a rotor having an annular peripheral propeller ring located therein adjacent the periphery thereof, an exhaust chamber outside of the 65 rotor separated by it from and communicating only through it with the central chamber, an apertured wall between the central housing chamber and the exhaust chamber, the aperture being in register with the annular ring.
18. A fluid turbine having a central housing chamber containing moving parts, a rotor having an annular peripheral propeller ring located therein adjacent the periphery thereof, an exhaust chamber outside of the 70 rotor separated by it from and communicating only through it with the central chamber, an apertured wall between the central housing chamber and the exhaust chamber, the aperture being in register with the annular ring, a nozzle inside the housing chamber discharging toward the propeller ring, and a channel between the nozzle and the bucket lips, said channel of a cross section substantially equal to or greater than the difference between the cross section of the 75 nozzle and the effective bucket opening.
19. A fluid turbine having a central housing chamber containing moving parts, a rotor having an annular peripheral propeller ring located therein adjacent the periphery 80

thereof, an exhaust chamber outside of the rotor separated by it from and communicating only through it with the central chamber, a partition wall located within the housing in front of the exhaust chamber and forming in part a nozzle-shaped passageway discharging toward the propeller ring in line with the discharge chamber.

20. A fluid turbine having a central housing chamber containing moving parts, a rotor having an annular peripheral propeller ring located therein, and an exhaust chamber outside the rotor, and connected with the central chamber through the rotor alone, 15 and a nozzle like opening from the housing

chamber into the rotor opposite the opening into the discharge chamber, a channel between the nozzle and the bucket lips, said channel of a cross section substantially equal to or not less than the difference between the 20 cross section of the nozzle and the effective bucket opening.

In testimony whereof, I affix my signature in the presence of two witnesses this 26th day of July, 1913.

CHARLES W. DAKE.
